CLAIM

The ornamental design for a golfer's accessory carrier or similar article, as shown and described.

DESCRIPTION

FIG. 1 is a front elevational view of a golfer's accessory carrier or similar article showing my new design;
FIG. 2 is a left side elevational view thereof, the right side being substantially a mirror image thereto;
FIG. 3 is a rear elevational view thereof;
FIG. 4 is a top plan view thereof;
FIG. 5 is a bottom plan view thereof; and
FIG. 6 is a perspective view thereof.
